UNITED STATES PATENT OFFICE.

HERMAN H. WENTHE, OF CHICAGO, ILLINOIS, ASSIGNOR TO MEYER & WENTHE, OF CHICAGO, ILLINOIS, A COPARTNERSHIP COMPOSED OF GUSTAVE MEYER, JR., AND HERMAN H. WENTHE.

ATTACHMENT FOR POCKET-SEALS.

1,165,474.

Specification of Letters Patent. Patented Dec. 28, 1915.

Application filed September 3, 1915. Serial No. 48,816.

To all whom it may concern:

Be it known that I, HERMAN H. WENTHE, a citizen of the United States, residing at Chicago, in the county of Cook and State of Illinois, have invented certain new and useful Improvements in Attachments for Pocket-Seals, of which the following is a specification.

The present invention relates to a base or holder adapted for use in conjunction with the so-called pocket type of seal, whereby it may be transformed from a pocket type to a desk type of seal and vice versa; and to means for attaching the base to the body of the seal and for drawing the base into desired close engagement with the seal body.

The objects of the invention are, to provide a base of simple and strong construction, which can be attached to the body of an ordinary pocket seal, whereby the seal may then be used as a seal of the so-called desk type; to provide a simple and effective means for attaching the base and seal, which means, when properly positioned, will act to draw the base into close and firm engagement with the body of the seal; and to arrange this attaching member so that it is of the shiftable variety, enabling a quick and easy attachment and detachment of the base from the body of the seal. And the invention further consists in the features of construction and combination of parts herein-after described and claimed.

In the drawings: Figure 1 is an elevation of the base of the present invention attached to a seal body; Fig. 2, a section on line 2-2 of Fig. 1, looking in the direction of the arrow; Fig. 3, a front elevation of a seal body with the base of the present invention attached thereto; and Fig. 4, a detail section on line 4-4 of Fig. 1, showing the removable member which attaches the base to the body of the seal and draws the base member into close engagement with said body.

In the art to which the present invention relates there are two main classes or types of seals, and by the term seal in the present application, is meant the form of implement used by notary publics and corporations for making the impression of their official seal upon documents. These two forms consist of the pocket type, which is a small and compact variety of a size and nature to enable it to be carried in the pocket, and the desk

type, which has a flat, substantial base, enabling it to set upright upon a desk. In the present invention, by the provision of a base member and suitable means for attaching or connecting the base member to the body of the seal, I am enabled to convert the seal from the pocket to a desk type, or vice versa, as may be desired, in a quick and simple manner.

Referring now to the drawings, the invention is illustrated in conjunction with a seal body, comprising what may be termed a fixed portion 5, and a movable portion 6, these parts acting in conjunction with one another to produce the jaw-like action always attendant upon seals of this character. No detailed description of the seal body is believed to be necessary in connection with the present application because of the fact that the present invention is not limited for use in connection with the particular sort of seal shown, except as defined by the terms of the appended claims; and attention is only called to the fact that the fixed portion 5 of the seal is formed with a depending lug 7, the purpose of which will be hereinafter explained.

The present invention deals, as stated, with a base or holder which is adapted to fit the seal so as to constitute a base therefor. This member, as shown, is of a one-piece construction, and consists of what may be termed a forward portion designated generally by the numeral 8, and which, in the construction shown, is of ring-like formation and adapted to receive the die portion 9 of the fixed part of the seal. Extending rearwardly from this forward portion 8 is an elongated portion 10, which may be termed the rear portion of the base. The lower face of the base is of a flat nature, so as to provide a broad and ample support for the seal member, and may, if desired, have secured thereto a pad of felt or other substance 10a, so that the metal will not contact and scratch the desk.

The portion 10 is, in the construction shown, formed with a depression 11, which forms a seat for the finger portion 12 of the fixed part 5 of the seal body. When the seal is placed on this base member, as shown in Fig. 1, a support is provided for the seal, so that it can set upright upon a desk and be used in the same fashion and manner as the

ordinary and well-known desk seal. It is desirable, however, that this base be capable of removal when desired, and it is also desirable that when the base is attached it 5 may be drawn into firm and close engagement with the body of the seal, as any looseness between the base and the seal would be detrimental and would not render the seal practical for use as a desk variety.

10 I have devised a very simple and efficient means for attaching this base to the body of the seal and for bringing about the close engagement referred to. As shown in the drawings, this combined joining and clamping member consists of a cotter pin 13, which is bent medially of its length to provide an offset portion 15, making the stem of the cotter of an eccentric character; and this cotter pin, when in use, extends through an 15 opening 16 in the flange 7 of the fixed portion of the seal and through oppositely disposed, alined openings 17 formed in opposite side walls of the base member. It might be stated that in the construction shown the 20 forward portion of the base is in the nature of a band made into the form of a ring, which band terminates and merges into the rear portion 10; and these openings 17 are therefore formed oppositely in the walls of 25 the forward band-like part of the base.

30 When the base is initially attached to the body of the seal, the attaching member is passed through the alined openings 16 and 17. Then by revolving this member a predetermined distance, the offset portion 15 will act to draw the base and body together, as in Fig. 1, thus joining the base firmly and rigidly to the body of the seal, so that, to all intents and purposes, it assumes the same 35 character as though it were an integral part of the seal. This converts the seal from the pocket type to the desk type and renders it practical for use as the latter type of seal. If so desired, the split end of the cotter may 40 be slightly spread, thus locking it in place and preventing accidental displacement; but it is obvious that at all times the attaching member may be quickly and easily withdrawn from position and the base removed, thus permitting of an easy and simple conversion of the seal back into the pocket type.

From the foregoing it will be apparent

that the invention is very simple and cheap of construction and provides a means for converting the seal from the pocket to the 55 desk type in a quick and simple manner.

I claim:

1. An attachment for pocket seals, comprising a base member adapted to receive the finger and die portions of the fixed part 60 of a pocket seal, and releasable means for attaching the base to the seal body, whereby the pocket seal may be converted to the desk type of seal, substantially as described.

2. An attachment for pocket seals, comprising a base formed of a band-like portion adapted to embrace the forward portion of the fixed part of a pocket seal, a plate-like portion extending from the band-like portion and adapted to receive the rear portion 65 of the fixed part of a pocket seal, and releasable means for attaching the base to the seal body, whereby the pocket seal may be converted to the desk type of seal, substantially as described.

75 3. An attachment for pocket seals, comprising a base adapted to receive the lower portion of the seal body, and a single shiftable member for attaching the base to the seal body, whereby the pocket seal may be converted to the desk type of seal, and said member when shifted acting to draw the attachment and seal body into tight engagement, substantially as described.

80 4. An attachment for pocket seals, comprising a base adapted to receive the lower portion of the seal body, said seal and base being formed with alined openings, a pin adapted to be inserted in said openings, a bend formed medially the length of said pin, 85 said bend when the pin is inserted lying within one of said openings and serving when the pin is rotated to draw the base and seal body into tight engagement, substantially as described.

90 5. An attachment for pocket seals, comprising a base arranged to receive the lower portion of a pocket seal, and releasable locking means for joining the base to the seal body, whereby said seal may be converted 95 to a desk type of seal, substantially as described.

H. H. WENTHE.
